VARIABLE TIME MECHANISM

Cary L. Wellington, Long Island City, N. Y., assignor to the United States of America as represented by the Secretary of War

Application January 3, 1947, Serial No. 720,040

9 Claims. (Cl. 102—81.2)

1

My invention relates to variable time mechanisms and while particularly adaptable to variable time, arming devices for bomb, shell, mine, grenade, rocket and like fuses, is readily adaptable for use with any other non-military mechanism for setting the same in operation at a predetermined future time.

With the foregoing in view, an object of my invention is to provide an improved variable time mechanism.

A further object is to provide an improved combination of a variable time mechanism and presetting tool therefor.

A further object is to provide novel pre-setting tool for a variable time mechanism.

Other objects and advantages reside in the particular structure of the invention, combination and arrangement of the several parts, and in the particular method of operation, all of which will be readily apparent to those skilled in the art upon reference to the drawing and following detailed description wherein the invention is shown, described and claimed.

In the drawing:

Fig. 1 is a longitudinal section through one form of the device;

Fig. 2 is a transverse section taken substantially on the plane of the line 2—2 of Fig. 1, but showing the parts in a different position;

Fig. 3 is an enlarged fragmentary longitudinal section of a part of Fig. 1;

Fig. 4 is a section on the line 4—4 of Fig. 3;

Fig. 5 is an end and elevation view of a detent;

Fig. 6 is a fragmentary longitudinal section showing the pre-setting tool in use;

Fig. 7 is a view like Fig. 6, but showing a knob and dial arrangement of pre-setting means; and

Fig. 8 is an elevation showing a modified form of pre-setting tool.

Referring specifically to the drawing, wherein like reference characters have been used throughout to designate like parts, a head member 10 is provided with any suitable source of power, in this case the wind driven vane 11. The vane 11 has a shaft 13 mounted in bearings 12 of head member 10. The inner end of shaft 13 extends inwardly of the head member and the inner end thereof mounts a pinion 14. Any suitable gear train, in this case a reduction gear train, connects the pinion 14 with a second pinion 15, which is rotatably mounted in a casing 9, which is connected to the head member 10, in any suitable manner as by being threaded thereto.

The pinion 15 is formed with an internally threaded axial bore and is threaded on the

2

threaded portion 16 of a variably-settable detent 17. The outer or head end of the detent 17 is cross-shaped or otherwise shaped in section, to provide a keyway, and is slidably fitted in a cylindrical passage 18 which is formed in and extends through the head member 10, parallel to the axis thereof. A spring-loaded latch member 19 is mounted in the head member 10 so as to extend into the passage 18 radially thereof for engagement in the keyway formed by the arms of the cross-shaped portion of detent 17 to prevent rotation thereof upon rotation of the pinion 15. The direction of rotation of the pinion 15 is such that it drives the detent 17 towards the outer face of the head member 10. The inner end 20 of the detent 17 is unthreaded and extends through a clutch connector member 21 and maintains the same out of engagement with a driving clutch member 22 which is constantly rotated by the gear train and which is freely rotatable with respect to a driven shaft 23. A spring 24 loads the connector 21 for movement in a direction to engage the driving clutch 22.

Any suitable gearing, as the gears 25 and 26, the former connected to the gear train aforesaid and the latter being rigidly connected to the driving clutch 22, constantly rotate the latter when the vane 11 is rotated. A driven clutch member 27 is fixed on the driven shaft 23, and the connector 21 is slidably mounted in a recess 21a, in one face thereof. The driven shaft 23 is connected to any suitable mechanism, not shown, which is to be operated or powered by the vane 11.

In operation, the detent 17 is screwed into the passage 18 a predetermined distance, depending upon the setting desired. It is understood that the rounded end of the member 19 permits a ratchet action, if sufficient pressure is applied. Thereafter, a predetermined number of rotations of the drive shaft 13 and pinion 15 causes the engagement of the internal threads of the latter with the threads 16 of the detent to move said detent in a direction to withdraw the unthreaded end 20 of the detent from its engagement with the connector 21, whereupon the spring 24 forces the connector 21 into one of the notches or recesses 22a of the driving clutch 22, and locks the same to the driven clutch 27. Thereafter, continued rotation of the drive shaft 13 will rotate the driven shaft 23, and the mechanism connected thereto.

In the embodiment shown, the device comprises an arming mechanism for a bomb fuse. However, this is but one of many applications of the device, and any suitable driving means may be substituted for the wind driven vane 11.

The pre-setting tools 40, shown in Fig. 6, may be of any suitable form and, as illustrated, comprises a screw driver 41 which is insertable in the opening 18, and which operatively engages the slot 11a of the shaft 17. A stop 42 is provided on tool 40 to engage the wall of casing 19 and thereby limit the distance the shaft 17 may be inserted.

To obtain a variable setting, a collection of tools 40 may be provided, each having a part 41 of the correct length for the setting desired. Or, as in Fig. 8, I may provide a setting tool 50 wherein the stop 52 may be adjustably positioned at any desirable point on part 51 according to the fixed scale 54. A set screw 53 or the like can lock stop 52 in the adjusted position.

Fig. 7 shows still another form of adjustment wherein the setting part 62 is provided with a cross-shaped slot 63 which slidably receives the cross-shaped shaft 17. The slot 63 is relatively long and the setting is read from the fixed and movable scales 64 and 65, respectively, upon rotation of the knob 60.

While I have shown and described what are now thought to be the preferred forms of the invention, it is obvious that the same is susceptible of other expressions and modifications. Consequently, I do not limit myself to the precise structures disclosed hereinbefore except as hereinafter claimed.

I claim:

1. A variable time mechanism, comprising a gear train, means for driving said gear train, a driving clutch member constantly rotated by said gear train, a driven clutch member normally disengaged from said driving member, a movable connector carried by said driven member, a spring loading said connector for movement into engagement with said driving member whereby to connect said clutch members together for rotation as a unit, a hole through said connector, a shaft having a free end extending through said hole to hold said connector out of engagement with said driving member, means mounting said shaft for axial movement, a threaded portion on said shaft inwardly of the free end thereof, a gear threaded on said threaded portion and in constant rotative engagement with said gear train, means preventing axial movement of said gear, means for preventing rotative movement of said shaft whereby rotation of said gear moves said shaft in a direction to disengage the free end thereof from said connector, and means for variably positioning said shaft relative to said connector to vary the time required to disengage said shaft and connector.

2. A variable time mechanism, comprising a gear train, means for driving said gear train, a driving clutch member constantly rotated by said gear train, a driven clutch member normally disengaged from said driving member, a connector carried by said driven member and movable to connect the same to said driving member for rotation therewith, a detent engaging said connector to hold the same out of engagement with said driving member and movable to disengage said connector and free the same for movement into engagement with said driving member, means movable by said gear train and operatively associated with said detent to move the same out of engagement with said connector, and pre-setting means for varying the time required to disengage said detent from said connector.

3. A variable time mechanism, comprising driving and driven clutch members normally disengaged from each other, driving means for ro-

tating said driving member, a connector movable to connect said clutch members for rotation as a unit, a detent holding said connector out of operative connection with at least one of said clutch members and movable to release said connector for operative connection with said clutch member, means driven by said driving means for moving said detent out of engagement with said connector, and pre-setting means for said detent to vary the time required to release the same from said connector.

4. A variable time mechanism, comprising driving and driven clutch members normally disengaged from each other, driving means for rotating said driving member, connecting means movable to connect said clutch members for rotation as a unit, means holding said connecting means out of operative connection with at least one clutch member, means actuated by said driving means for releasing said holding means from said connecting means, and pre-setting means for varying the time required to release said holding means from said connecting means.

5. A variable time, arming mechanism for a fuse, comprising a driven arming shaft, a driven clutch member fixed on said shaft, a driving clutch member normally disengaged from said driven member, connecting means for connecting said clutch members together for rotation as a unit, actuating means for actuating said connecting means to connect said clutch members, driving means for said driving clutch member and said actuating means and pre-setting means for varying the time required for actuating said connecting means.

6. A variable time, arming mechanism for a fuse, comprising a driving clutch member and driving means for the same, a driven clutch member normally disengaged from said driving member, means actuated by said driving means for operatively connecting said clutch members, and pre-set means for varying the time of actuation of said connecting means.

7. A variable time mechanism, comprising a casing, a gear train in said casing, means for driving said gear train, a driving clutch member in said casing and rotated by said gear train, a driven clutch member in said casing normally disengaged from said driving member, a movable connector carried by said driven member, a spring carried by said driven member and loading said connector for movement radially of said driven member into operative engagement with said driving member to operatively connect said clutch members, a hole through said connector, a shaft in said casing having a free end extending into said hole a selectively varying distance to hold said connector out of engagement with said driving member, means mounting said shaft in said casing for axial movement, a threaded portion on said shaft, a gear threaded on said threaded portion and rotatably connected to said gear train, means preventing axial movement of said gear, means carried by said casing for preventing rotatable movement of said shaft whereby rotation of said gear moves said shaft in a direction to withdraw from said hole at the free end thereof, said shaft being adapted to be pre-set in said casing and connector to vary the time required to disengage the same from said connector.

8. The structure of claim 7, said means for preventing rotation of said shaft comprising a plurality of splines on the other end of said shaft and a spring-loaded latch carried by said casing and engageable with said splines.

9. The structure of claim 7, said means for preventing rotation of said shaft comprising a plurality of splines on the other end of said shaft and a spring loaded latch carried by said casing and engageable with said splines, means for pre-setting said shaft, comprising an access opening in said casing for the splined end of said shaft adapted to receive a pre-setting tool engageable with the splined end of said shaft.
